UNITED STATES PATENT OFFICE

EMMETT B. MOORE, OF EVANSTON, ILLINOIS

HOSE NOZZLE

Application filed June 13, 1930. Serial No. 460,808.

This invention relates to hose nozzles and the like, and has for an object to provide a nozzle of improved and simplified construction which is adapted to be quickly and easily 5 adjusted for producing a relatively small stream or spray, or a comparatively large stream or spray substantially equal to the full capacity of the conduit supplying the liquid. Another object is to provide an improved 10 nozzle having a plurality of valves, and a common operating member for successively opening or closing the respective valves. It consists in certain features and elements of construction herein shown and described, as 15 indicated by the claims.

In the drawing:

Figure 1 is an axial section through a nozzle embodying the present invention, showing both valves in closed position.

Figure 2 is a transverse section taken substantially as indicated at line 2-2 of Figure 1.

Figure 3 is an enlarged perspective view of the duplex valve element.

Figure 4 is an enlarged fragmentary longitudinal section, showing both of the valves in their full open position.

Figure 5 is a perspective view of the replaceable valve seat.

In the construction illustrated in the drawing, the nozzle fitting includes a coupling member, 10, which is interiorly threaded at one end for connection with the usual coupling member of a hose or the threaded end 35 of any suitable form of conduit. This coupling member is provided with a reduced tubular extension 11, on the outer end of which an operating sleeve, 12, is threaded and arranged for rotative axial movement thereon, which movement controls two concentrically 40 arranged valves located adjacent the outer end of said sleeve, as hereinafter described. Preferably cast integral with the interior of the extension, 11, is a spider, 14, with which 45 is rigidly associated a centrally disposed needle valve member, 15, which is herein shown as a separate element having its rear end riveted over as indicated at 15^a, in said spider. As may be seen in Figure 1 of the 50 drawing, this needle valve element extends

a substantially distance beyond the outer end of the tubular extension, 11, and has its extreme end conically formed as indicated at 16, which serves as the valve proper. Slidably mounted on the outer end of said needle valve member is a part, 18, disposed wholly within the operating sleeve, 12, and which, for convenience, may be termed a "duplex" 55 valve element because it serves as a seat for the inner valve and is in effect the valve proper for the outer valve, as will hereinafter be seen.

The "duplex" valve element includes a sleeve, 19, which fits snugly around and is axially movable on the needle valve member, and which sleeve is provided with a pair of diametrically opposite longitudinally extending slots, through which extends a cross pin, 21, projecting diametrically through the needle valve element. The pin and slots thus prevent rotation of said "duplex" element on the needle valve member and serve to define the limits of axial movement of said "duplex" element relative thereto. Integrally formed with the sleeve, 19, of the "duplex" element 60 is an annular portion, 22, the inner surface of which, as indicated at 23, serves as the seat for the conical valve, 16, which controls the inner valve port or orifice, 23^a, in said "duplex" element, while the exterior surface of 65 said portion, 22, is formed frusto-conically, as indicated at 24, and serves as the valve member for the outer or supplementary valve. The annular portion, 22, and the sleeve, 19, of the "duplex" element are connected by a plurality of longitudinally extending ribs, 25, which are radially offset relative to said needle valve member, 15, as 70 seen in Figures 3 and 4, so as to insure passage of the liquid therebetween for discharge 75 through the central orifice, 23^a, in the annular portion, 22.

To further insure true axial movement of this "duplex" element I form said element 80 with a plurality of radially extending fins, 26, which are dimensioned to substantially engage the inner wall of the operating sleeve, 12, and preferably these fins are located in alignment with the respective ribs, 25, so as 85 to reduce the obstruction to the flow of the 90

liquid through the fitting to a minimum. Adjacent the outer end, the operating sleeve, 12, is formed with an internal stop shoulder, 28, against which abuts a removable valve seat element, 29, whose seat, 30, cooperates with the valve, 24, of the "duplex" element for controlling the port or orifice, 29^a, in the seat, 29, which constitutes the outer valve. A retaining fitting, 32, is threaded into the outer end of the operating sleeve, as may be clearly seen in Figure 4, and is arranged to abut and firmly lock the seat, 29, in position against said shoulder, 28, of the operating sleeve. The seat, 29, may be made of any suitable material such as metal, fibre, rubber, etc. Preferably it is held against rotation with respect to said operating sleeve, and to so maintain said seat, it is formed with one or more laterally projecting lugs, 33, which are adapted to register in correspondingly formed slots, 34, provided in the stop shoulder, 28. By virtue of this construction it will be apparent that this valve seat element, 29, may be quickly and readily replaced if necessary when it becomes worn or mutilated merely upon the removal of the retainer member, 32.

The "duplex" element is normally yieldingly urged in an outward direction, tending to maintain its valve, 24, in engagement with its cooperating seat, 30, in the sleeve, 12, by means of a coil spring, 36, circumscribing the rear end of the needle valve member and reacting between the spider, 14, and a washer element, 37, disposed against the end of the sleeve, 19, of the "duplex" element. Thus when the operating sleeve, 12, is threaded onto the coupling extension, 11, the "duplex" element by reason of the contact of its valve, 24, with the seat, 30, is gradually moved rearwardly along the needle valve member until the seat, 23, of the "duplex" element is brought tightly in contact with the conical valve proper, 16, of the needle valve member, in which position the spring, 36, is under substantial compression. It will now be apparent that when the operating sleeve, 12, is rotated opposite-
ly, or outwardly with respect to the exten-
sion, 11, of the coupling, the spring will tend
to hold the valve, 24, of the "duplex" ele-
ment tightly against its seat, 30, in the end
of the operating sleeve, 12, through a limited
range of axial movement of said operating
sleeve, determined by said cross pin, 21, and
slots, 20, and afforded by the threaded con-
nection of said sleeve on the coupling exten-
sion. Such movement of the operating sleeve
gradually shifts the seat, 23, of the "duplex"
element away from its cooperating cone, 16,
of the needle valve member, 15, so as to per-
mit a flow of the liquid through the inner
valve orifice, 23^a, controlled thereby, either
as a spray or stream, depending upon the
effective shape and size orifice.

Since the "duplex" element is positively held against rotation with respect to the coupling extension, it will be observed that during axial rotative movement of the operating sleeve in opening or closing the inner valve consisting of the seat, 23, and the cone valve, 16, the seat, 29, of the outer valve will be rotated with respect to its non-rotative valve member, 24, of the "duplex" element, which action tends to grind and insure a more perfect seat for the valve member, 24. After the operating sleeve has been rotated and axially shifted outwardly to the extent that the "duplex" element is moved to its outermost limit by the spring, 36, as determined by the length of its slots, 20, then upon further rotation of the operating sleeve in the same direction the outer seat, 29, will be gradually moved away from the valve, 24, of the "duplex" element, thereby opening the outer or supplementary valve port, 29^a, which provides a substantially increased flow, approximately equivalent to the full capacity capable of being discharged through the extension, 11, of the coupling. The two valves are thus opened in successive order, and obviously when the operating sleeve, 12, is rotated inwardly after said valves have both attained their full open position, the outermost valve will be first closed,—that is, the seat, 29, will first be brought into contact with the valve, 24, of the "duplex" element, closing the orifice, 29^a; and continued rotation will cause the "duplex" element to be gradually moved rearwardly on the member, 15, compressing the spring, 36, and gradually moving the seat, 23, of the "duplex" element toward its cooperating cone valve, 16, on the end of the needle valve member for closing the orifice, 23^a, of the inner valve.

As is generally understood, in valves of this character when the valve is just "cracked" off of its seat the flow of the liquid through the orifice controlled by the valve seat is caused to take the form of a spray and as the effective valve opening is increased, the spray gradually takes the form of a concentrated stream. Thus by this construction the inner valve member may produce either a relatively small stream or spray and when it is desired to have a greatly increased flow or capacity the outer valve may then be opened in addition. To insure obtaining a relatively wide spray when the outer valve is in a partially open position, I preferably form the annular portion, 22, beyond the valve, 24, of the "duplex" element with a reversely curved annular bead, 38, which serves to deflect the liquid in a manner to cause a wide conical spray; the shape of the exterior surface of the seat, 29, and the retaining member, 32, being properly designed so as to assist in this result also. In Figure 4, the "duplex" element is shown at a position corresponding to substantially maximum opening of the outer

valve, which will produce a relatively concentrated large capacity stream.

To insure against leakage between the threaded connection of the extension, 11, and the operating sleeve, 12, I preferably provide a suitable packing element 40, adjacent the rear end of said operating sleeve and which is tightly held in place by a packing ring, 41, threaded onto the rear end of the said sleeve, as shown in Figure 1.

Although I have shown and described a preferred embodiment of my invention, it will be understood that the construction and arrangement of parts may be varied without departing from the spirit and scope thereof. I therefore do not wish to be understood as limiting myself to the particular construction illustrated, except as indicated in the appended claims.

20 I claim:

1. A nozzle fitting comprising in combination with a coupling having a tubular extension containing an integrally completely circumferentially enclosed and axially extending flow passage, a valve member rigidly carried by said coupling extending axially through said tubular extension and having its terminal constituting a valve; a double-function member, constituting both a valve and a valve seat, mounted slidably on said rigid valve member for cooperation of its valve seat feature with the valve terminal of said rigid valve member, means automatically stressing the double-function member in the direction for withdrawing the valve seat thereof from said valve terminal and means for limiting said withdrawal movement; the tubular extension being exteriorly threaded over the terminal portion of its length and a tubular nozzle discharge member interiorly dimensioned for encompassing the tubular extension, the double-function member and the rigid valve member, and having at its outer end an interior annular seat for the valve element of the double-function member and interiorly screw-threaded for screwing onto the tubular extension to carry said interior annular seat to seating contact with the valve element of the double-function element when the latter is seated on the terminal valve of the rigid valve member.

2. A nozzle fitting comprising in combination with a coupling having a tubular extension containing an integrally completely circumferentially enclosed and axially extending flow passage, a valve member rigidly carried by said coupling extending axially through said tubular extension and having its terminal constituting a valve; a double-function member, constituting both a valve and a valve seat, mounted slidably on said rigid valve member for cooperation of its valve seat feature with the valve terminal of said rigid valve member, means automatically stressing the double-function mem-

ber in the direction for withdrawing the valve seat thereof from said valve terminal and means for limiting said withdrawal movement; the tubular extension being exteriorly threaded over the terminal portion of its length and a tubular nozzle discharge member interiorly dimensioned for encompassing the tubular extension, the double-function member and the rigid valve member, and having at its outer end an exterior annular seat for the valve element of the double-function member and interiorly screw-threaded for screwing onto the tubular extension to carry said interior annular seat to seating contact with the valve element of the double-function element when the latter is seated on the terminal valve of the rigid valve member; said nozzle discharge member being extended inwardly beyond its threaded portion and furnished with a packing ring cooperating with the inner end portion of the tubular extension beyond the thread thereof for liquid-tight sealing the joint between said tubular extension and said nozzle discharge member.

3. A nozzle fitting comprising in combination with a coupling having a tubular extension containing an integrally completely circumferentially enclosed and axially extending flow passage, said extension being exteriorly threaded for receiving an additional extension member, and an extension member screwed onto said tubular extension and extending therebeyond for constituting the nozzle discharge and furnished with an interior annular valve seat encompassing its discharge opening; a valve member carried rigidly by the coupling extending axially through said tubular extension and by its terminal constituting a valve for measurably controlling the nozzle discharge; a double-function member, constituting both a valve and a valve seat axially apertured for accommodating the rigid valve member extending into it and with respect to which it is axially movable, the valve seat feature of said double-function member being interior at the outer end and arranged to cooperate with the terminal valve of the rigid valve member, the valve feature of said double-function member being exterior, and means holding said double-function member non-rotatable with respect to the rigid valve member.

4. A nozzle fitting comprising in combination with a coupling having a tubular extension containing an enclosed flow passage, said extension being exteriorly threaded for receiving an extension member and a nozzle extension member screwed onto said tubular extension and extending therebeyond and constituting the nozzle discharge and furnished with an annular valve seat encompassing its discharge opening; a valve member carried rigidly by the coupling extending concentrically through said tubular extension and by

- its extremity constituting a valve for measurably controlling the nozzle discharge; a double-function member, constituting a valve and a valve seat, carried slidably on said first mentioned valve member and beyond the slide bearing part thereof having a chambered enlargement apertured for flow communication of said chamber with the cavity of the nozzle extension member, said enlargement constituting exteriorly a valve adapted to seat at the annular seat of the discharge of the nozzle extension member and interiorly formed with an annular seat for the first mentioned valve member.
15. 5. The construction defined in claim 4, the double-function member being mounted for limited range of movement longitudinally of the rigid valve member, and means for holding it normally at the forward limit of said range.
6. The construction defined in claim 1, the valve terminal of the rigid valve member being conical and the range of movement of the double-function member with respect to said valve terminal being more than the distance which said conical terminal extends through the valve seat when fully seated; whereby the adjustment for varying the opening for discharge controlled by the valve and seat is adapted to vary the discharge from direct jet to more or less widely spread spray.
7. The construction defined in claim 1, the valve seat at the discharge of the nozzle discharge member and the valve element of the double-function member being cooperatively frusto-conical and the range of adjustability of said nozzle discharge member being sufficient to separate said valve and valve seat further than the width of the zone of the frusto-conical seat of the nozzle discharge member.
